Christian Knisely of Moadville, co^t of Crawford,
State of Pennsylvania

Letters Patent

The schedule referred to in these Letters Patent, and making part of the same, containing a description of the words of the said Christian Knisely himself of his improvement in the manner of making and covering Bedsteads.

To all to whom these Letters shall come
Be it known, that I Christian Knisely of Moadville in the
county of Crawford and state of Pennsylvania, have invented a new
and useful improvement in the manner of constructing Bedsteads, of
that the following is a full and exact description of the construction
and operation thereof:

Firstly. - The rails and posts of the Bedstead are connected together by right angled triangular dove tail tenons, made in the following manner. - First. - strike round the rail by a square, one and one half inches from the end, then draw a line parallel with the rail, three inches from the outside, which will leave a shoulder of one and a half inch upon the inside the rail, being four and a half inches square, then establish a point on the line across the rail with one fourth of an inch of the outside, then draw a line from that point to intersect with the parallel line at the end of the rail, which forms the right angled triangle in shape of the tenon, across the rail and go through with the same process as before, and the tenon will be formed, with the exception of the dovetail, leaving also a shoulder on the outside one fourth of an inch, the dovetail is laid out after the tenon is worked off from the rail with the inside up, establishes points for the laying out of the dovetail on the inside of the tenon at the shoulder, half an inch from the bottom and top of the rail, then draw lines from those points, touching the corners of the tenon at the end of the rail, which completes the draft or shape of the dovetail, it having a termination at the first established point, then along the angle of the tenon to the

extreme corner of the angle.

Secondly - A description of the mortise, which is trapezoid in shape when the batten enters the post - Strike two lines square across the post the size of the rail apart, then draw two parallel lines lengthwise with the post, one a fourth of an inch, the other two inches from the outside, then establish two points on the second parallel line, half an inch within these lines along the post, then draw lines from these points, touching the intersection of the other parallel and two wavy lines, which will complete the trapezoid, trim the mortise on the shape that the batten may fit, the batten will enter easily by placing the extreme angle of the batten, at the extreme angle of the mortise which will be at the first parallel line - The rail may be braced on, as shown in one end of the Model -

Thirdly - A description of the head and foot boards which are so arranged as to admit of being put on and taken out, without unfastening the Bedstead, by breaking the posts where the boards enter, the bushes or blocks are turned the diameter to be one and a half inch, by one and three fourths of an inch long, with a socket one inch diameter, by three fourths of an inch deep, at one end of the boards, the bushes are put in solid, with glue and the opposite end is arranged by means of a wire spiral spring attached to the end of the bush at the bottom of the hole, so as to admit, the bush to be forced in sufficiently to cover the batten at the other end the batten may be made square or round and square on the same principle.

Fourthly - A description of the sacking, how made, in what manner attached to the walls, and how strained - The sacking is made in four triangular pieces, the length of one side of each of the side pieces being equal to the length of its corresponding side wall, the other two sides of each piece being cut so as to leave a space of five inches in the centre of the bedstead between the two points, the length of one side of each of the end pieces being equal to the length of its corresponding end wall, the other two sides of each piece being cut so as to leave a space of six inches in the centre between these two points, which makes the space where the batten comes in, equal - There should be a small cord worked into the

hem of the sacking all round the hem in the side which is attached to the rail, requires to be about three inches broad, with a cord in it sufficiently large to prevent its drawing out of the sail, each rail having a hole perforated from end to end inside of the hem, half an inch diameter, which is bored, after having sawed a groove along the under of the sail upon the inside as low as the hem, and having run an iron wire through the sawing to make an opening to guide the front of the auger, the sawing must be large enough to admit two thicknesses of the sacking into which the sacking is drawn, the cord in the hem passing along in the hole, which prevents its drawing out, each piece, however, should be cut long enough on the side that is attached to the rail, to admit the points to be clipped off, so that the ends of the cord in the hole running from the centre of the bedstead touch the ends of the sail upon the inside, these should have eyelet holes at each corner, the corners or points of the end pieces at the corners of the bedstead, should have two eyelets opposite, as near the point as may be, the intermediate space should be divided into a suitable number of eyelets and so arranged as to admit of the cord passing regularly from one to the other alternately, commencing at the centre of the bedstead, the Jack being attached at the centre and the cord being in two pieces, and each piece drawn half its length through the arbor in the Jack, on arriving at the post, the cord is passed round a hook in the corner of the post and made fast, the corner of the post, where the hook is screwed on, is taken off to the nail. The second Jack is then applied, until the sacking is sufficiently obtained, which completes it as shown on draft No. 1. 0. 0.

Draught No. 2. presents sacking of a different shape being cut into four oblong squares, leaving a space of four inches from the centre of the bedstead to the centre of each rail, the siderails are made in the same manner as described above, and found on Draught No. 1. with the exception of an opening made at the centre of the sail, say half an inch by four inches long and as deep as the groove, at which place the sacking is drawn in, and fastened by means of eyelets in the sacking, to the iron hooks in the end rails which are ground out.

with a half-round, and along it the hooks screwed in so as to come out but little more than flush with the inside of the rail. This method of arrangement will prevent the sacking to be put on, and taken off without separating the bed-lead; it is laid in the same manner as the other, commencing at the centre.

Fifthly A Description of the hooks, with policies on. The hook may be made of wire, one-fifth of an inch in diameter, the end to receive the policy turned up at a right angle, three-fourths of an inch long, the policy being a little less in thickness so as to avoid of being rotated slightly after being put on, the diameter about three-fourths of an inch these hooks and policies are designed for bed-leads without sacking, they are screwed in along the centre of the rail when the inside, the rail being grooved out with a half-round as shown on Draft No. 2 each rail should have an odd number of hooks, the odd hook to be placed at the centre of the rail so that the cords proceeding from the Jack; which is also stationed at the centre, will run at right angles when secured and the cords made fast at the corners, the Jack is applied until sufficiently strained.

Sixthly A Description of the screwing Jack and directions how to make it. Take a block four by five inches and eight inches long and number the four sides as follows: 1, for instance is the top wide five inches 2 is the side for the wheel, four inches away 3. the underside, five inches wide 4. the opposite side to the wheel, four inches; strike round the centre of the block by a square, establish two opposite points on the centre of the block on sides No. 2 and 3 for the centre of the arbor, one side No. 2 bore a hole, three and a half inches diameter, one inch deep for the tooth wheel, then reduce it to one and a fourth inch diameter for the arbor on the wheel, and bore through the block, then draw a circle across sides No. 2, two and one sixteenth inch at the right hand of the former circle for the centre of the apical arbor, square or divide across sides No. 1 and 3. On this establish two opposite points, eleven and one-fourth of an inch from side No. 2. Then bore a hole from side No. 3 one inch in diameter and three inches deep, then from side No. 1 bore a hole five eighths of an inch diameter into the other; for the nut.

of the arbor, the arbor is five inches long exclusive of the head on the lower end, which should be large enough to prevent its drawing into the block with a hole through it to run a line through, the arbor commences at the neck and runs down two inches, is a square thread, cut as deep as the neck on the upper end of the arbor. Turn up side N°. 9 and lay out a boxing to give room for winding the cord round the first mentioned arbor, strike two lines parallel with the block, one a quarter of an inch, the other three inches and three quarters from side N°. 11; then from the scribe first struck round the block, strike two others parallel with it, one each side, one and three fourths of an inch distant and the box is laid out, then turn up side N°. 1, and establish a point on the line running across the centre of the block two inches from side N°. 11 and bore a hole one inch and a quarter diameter through into the boxing below, which will be about one inch through, round the upper corner at four different points, which will steady the block and prevent its cutting the cord. The wheel mentioned is metal, three and an half-inch diameter, half an inch or five eighths of an inch thick with a square hole in the centre, seven eighths of an inch diameter to fasten on the arbor, the arbor may be cast on the wheel, in that case three fourths of an inch in diameter will do, the arbor on the top of the wheel passes through the block, and a pin fast through it to keep it in its proper place, it must have two holes through it at right angles about the centre of the box, large enough to let the cords pass through

What I claim as my own invention and not previously known in the above described Bedstead, is first, the manner of forming the rails into the posts, secondly, the method of fastening in the head and foot Boards. Thirdly, the mode of attaching the Sacking to the rails and the general arrangement of the sacking. Fourth, the Books with pulleys used in cording, as described on the Specification and fifthly the Task used to strain the cords and sacking with.
